UNITED STATES PATENT OFFICE.

FRANK P. SHEK, OF BROOKLYN, NEW YORK.

LOCK.

Application filed March 8, 1922. Serial No. 541,920.

To all whom it may concern:

Be it known that I, FRANK P. SHEK, a citizen of the United States, and a resident of Brooklyn, county of Kings, and State of New York, have invented certain new and useful Improvements in Locks, of which the following is a specification.

This invention relates to an improved lock that is adapted for many purposes and can be quickly snapped shut, and is preferably releasable by a key, and further, is substantially flat and comparatively small, so that it can be easily carried in the pocket.

The lock is further designed to provide a means for suspending articles from the shackle when the shackle is fixed to a support, and is also designed so that the lock itself can be secured both to the article to be suspended and itself, in turn, suspended from a fixed object and locked thereto, which construction also makes it possible to use the lock for fastening two elements together, such as mail bags or the like, so that they will not become accidentally separated.

The invention is illustrated in the accompanying drawing, in which Figure 1 is a side view of one form of lock embodying my invention, the lock being open so that its lower loop or end is accessible for the securing of an object thereto. Figure 2 is a side view with one of the plates of the lock casing removed and the lock casing slid down so that it bridges an opening in the shackle to close the lock. Figure 3 is a view similar to Figure 1, but with the casing slid down to open the other end of the shackle. Figure 4 is a section on line 4—4 in Figure 1. Figure 5 is a perspective view of the parts of the casing separated, and Figure 6 is a detail view showing a modified form of the upper portion of the shackle.

The shackle can be made of any desired material, but is preferably made of very stout round wire, and is formed with a strand 10 and has closed ends, usually by bending the wire in a return bend so as to form open loops, these return bends 11 and 12 merging into the strand 13, which strand 13 has an opening therein, since the ends of the wire are spaced apart; in other words, do not meet, and it is through this opening that the articles to be suspended or locked are passed into the closed ends of the lock.

The casing 14 slides on the shackle by having a portion thereof encircling both

strands of the shackle, and the preferred form of lock casing that I employ consists of two plates 15 and 16 which are recessed at 17 and 18, respectively, at the top and bottom, which top and bottom edges are flanged, as at 19, these recesses 17 and 18 forming openings for the passage of the strands of the shackle.

The plates 15 and 16 are suitably secured together, but I may use a combined securing means and spring holder consisting of a bar 20 which has studs or pins 21 projecting from the opposite sides, which fit through holes 22 in the plates 15 and 16 and are then headed, as at 23, to secure the parts together. The bar can be utilized to hold the spring 24, which is fastened to the bar 20, by any suitable means, such as by bending over the bar, as at 25, to embrace the end 26 of the spring to keep the spring from rising, the spring having its end 27 bent preferably at right angles or transversely to the strand 10.

The strand 10 has a detent 28 which is disposed so that when the casing bridges the opening in the shackle the end 27 of the spring 24 snaps into the detent and is held therein against longitudinal movement, so that the casing is locked in this position.

Suitable releasing means, such as the key 29 insertible through the key-hole 30, can be used to release the spring. When the spring is released and the casing is slid to uncover the opening, the friction of the spring will usually hold the casing in non-locking position, but to hold it so that it fully uncovers the opening and is held in position either under vibration or jarring, I provide a recess 31 in the strand 10 into which the end of the spring 24 rests, but it only holds the casing lightly, because by simply taking the casing between a finger and the thumb of one hand the casing can be dislodged and slid down to locking position.

The lock is adapted for use in closets and wardrobes, and in public places where coats are hung up, and in such form the shackle can be made so that it can be attached to a wall, Figure 6 illustrating one form in which the closed loop 32 is formed at the top end of the strand 10 and the wire then extended to form the open loop 11, the loop 32 forming an eye, through the opening 33 of which a suitable screw can be passed for fastening the device to a wall.

If the device is to be used for securing two elements together it can be used as above described, which description has illustrated how the open loop 12, which forms a hook, can be opened and closed, but in case the other end 11 is to be used, the lock is unlocked and the casing can be slid down, as shown in Figure 3, to uncover the end 34 of the strand 13, so that the upper 10 loop or hook is available, and while I may make the lock so that only one end of the shackle can be made accessible through the opening in the shackle, I prefer to make it so that both ends can be used, that is, the 15 casing can be slid to both sides of the opening.

To permit its use in a wardrobe, the lower loop or hook 12 at its end 35 can be rounded to prevent perforation of coats or articles 20 caught on it, and in this case there is enough clearance between the end 35 and the opening that it enters to allow a fold of the material to be grasped thereby, which will be clear from Figure 2.

25 This lock is found advantageous also in places where it is necessary to preserve such things as burlap bags and similar articles from theft, in that they can be caught over the hook 13 after they are emptied, such as 30 in rubbish collections and the like, and then by simply pulling down the casing 14 the bags are locked in position.

I claim:

1. A lock comprising a shackle formed 35 into open loops at the ends, the ends of the strand at one side being spaced apart to

form an opening, and a casing slidable on the shackle, the casing and shackle having co-acting means to lock the casing in position when it bridges the opening, the casing 40 and shackle also having co-acting means to frictionally hold the casing in non-locking position.

2. A lock comprising a shackle with parallel strands and closed ends, and having an 45 opening in one of the parallel strands, a casing slidable to both sides of the opening, and means for locking the casing in position when it bridges the opening.

3. A lock comprising a shackle formed 50 of parallel strands and having closed ends, one of the strands having an opening therein, a casing formed of plates with recesses 55 therein so that the assembled plates will slide on the strands, a bar having projections thereon, the plates of the casing having openings through which the projections can pass and be headed, a spring secured to the bar with its end bearing on one of the strands and substantially at right angles 60 thereto, said strand having a detent disposed so that when the spring is in it the casing is locked when in position across the opening, said strand having also a slight depression disposed so that when in engagement with the spring it will hold the casing frictionally in non-locking position.

In testimony that I claim the foregoing, I have hereto set my hand, this 2nd day of March, 1922.

FRANK P. SHEK.
